UNITED STATES PATENT OFFICE

147,689

DESIGN FOR A SMOKING PIPE OR SIMILAR
ARTICLEAugust R. Schwan and Jay P. Clymer,
Lancaster, Pa.

Application March 5, 1946, Serial No. 127,111

Term of patent 14 years

(Cl. D85—8)

To all whom it may concern:

Be it known that we, August R. Schwan and Jay P. Clymer, citizens of the United States, residing in Lancaster, county of Lancaster, and Commonwealth of Pennsylvania, have invented a new, original, and ornamental design for a Smoking Pipe or Similar Article, of which the following is a specification, reference being had to the accompanying drawing, forming a part hereof, and in which

Figure 1 is a view in elevation of the rear of a smoking pipe or similar article showing our new design;

The dominant features of our design reside in the portion shown in solid lines.

We claim:

The ornamental design for a smoking pipe or similar article, substantially as shown and described.

AUGUST R. SCHWAN.
JAY P. CLYMER.
